UNITED STATES PATENT OFFICE.

OSCAR F. BURTON, OF BELLEVILLE, NEW JERSEY.

DESIGN FOR A SPROCKET-WHEEL.

SPECIFICATION forming part of Design No. 25,803, dated July 21, 1896.

Application filed April 7, 1896. Serial No. 586,606. Term of patent 14 years.

To all whom it may concern:

Be it known that I, OSCAR F. BURTON, a citizen of the United States, residing at Belleville, in the county of Essex and State of New Jersey, have invented and produced a new and original Design for Bicycle Double-Rim Sprocket-Wheels, of which the following is a specification, reference being had to the accompanying drawing, forming a part thereof, which is a perspective view of a sprocket-wheel embodying the features of the design.

The design consists in two concentric rims A and B, one of less diameter than the other, the two rims being in such close relation as

to appear integral, and the peripheral surface 15 of each rim is offset at intervals, the offsets appearing as teeth. The larger rim only is connected with a hub-center, the smaller rim appearing apparently as non-supported, whereby the entire wheel is given an airy, 20 light appearance.

I claim—

The design for a double-rim sprocket-wheel for bicycles, herein shown and described.

OSCAR F. BURTON.
